THERMALLY CONTROLLED ELECTRIC
RELAYElihu Craig Thomson, Boston, Mass., assignor to
Photoswitch, Incorporated, Cambridge, Mass.,
a corporation of Massachusetts

Application December 9, 1943, Serial No. 513,563

8 Claims. (Cl. 200—122)

1

This invention relates to electric switches and more particularly to thermally actuated rapidly operating spring switches.

It is one of the main objects of the present invention to provide a switch of this type which on the one hand lends itself especially well to rapid or snap operation and on the other hand to operation by a controlling condition which can be translated into a mechanical effect, for example by heat and, generally, to provide a switch of this type which is simple and rugged in construction and yet very sensitive, easily adjustable and versatile in application.

Other objects are to provide a switch which responds to a predetermined temperature, independently of the ambient temperature; to provide a switch the time delay of which is independent of ambient temperature; and to provide a switch which responds positively to the combined effect of two varying temperatures.

Further objects are to provide a quick action or snap switch which is positively controlled by a temperature responsive element; to provide a switch of this type having tension and compression spring members whose switch elements are positively retained in operative relation with the temperature responsive controlling elements by the play of forces inherent in the construction as a whole, with a minimum of fastening elements; to provide a switch of this type whose temperature-responsive elements are subjected principally only to tension; to provide a switch of this type which lends itself well to inexpensive, compact and yet safe assembly within a protective housing; and to provide electronic relay circuits which require very little output current, which are free from characteristics detrimental to the life of discharge tubes, and are generally advantageous under certain operating conditions.

In carrying out my invention I employ flexible actuators firmly mounted at one point whereas another point of each actuator is positively connected with a corresponding point of the other actuator through a rigid link. At least one of these flexible members is thermoresponsive, formed for example of a bimetal strip provided with a heating resistance. A point of the connecting link, between or on one side of the connected actuator points, is associated with an operating member of the switch in question, for example the free end of the tension or compression spring of a snap action switch of known construction, such as for example described in Patent No. 1,960,020. This arrangement permits

realization of the above-mentioned objects since the two actuator members are rigidly coordinated, so as to combine their bending forces which forces depend upon the effective temperature of the actuator; this temperature may be either ambient or determined by a controlling heater element.

In another aspect of the invention, the actuators are strips arranged in the general direction of the lines of stress of the spring members of a snap switch. The connecting link is fastened to one spring member so as to operate it. If the connector or link is thus joined to actuators and switch spring, for example with the actuators tensioned to take up the stress of the tension member of the switch, the operative association of actuators, connector and switch member is positively sustained in the simplest possible way. This mode of correlation also has the advantage of subjecting the actuators almost entirely to axial stress, thus largely avoiding unfavorable bending moments which might affect the accuracy of operation.

These and other objects, aspects and features will be more fully apparent from the following description of several practical embodiments illustrating the genus of the invention. The description refers to drawings in which

Fig. 1 is a side view, with a front cover block removed, of a switch according to the present invention with two individually heated actuators;

Fig. 2 a section on line 2—2 of Fig. 1;

Fig. 3 a section on line 3—3 of Fig. 1;

Fig. 4 an expanded section of the switch elements proper, on line 3—3 of Fig. 1;

Fig. 5 a side view similar to Fig. 1 but with both cover blocks removed;

Fig. 6 a front view of a second embodiment of the invention with one heated actuator;

Fig. 7 a section on line 7—7 of Fig. 6;

Fig. 8 the vertical section, similar to Fig. 2, of a third embodiment of the invention in which the actuators are not provided with heating elements;

Fig. 9 an axonometric view of the insulation sleeve upon which the heater is wound as shown in Fig. 4;

Fig. 10 an axonometric representation of the switch spring, in two embodiments;

Fig. 11 a schematic representation of an embodiment of the invention with the actuators on one side of the switch; and

Fig. 12 the diagram of a circuit incorporating a switch according to the invention.

In the embodiment shown in Figs. 1 to 6, the

switch according to the invention is mounted in an insulating housing made for example of molded plastic. The housing herein shown and described is of a construction which is particularly suited for this purpose but which is not part of the present invention and constitutes the subject matter of copending application Serial No. 513,571 filed on December 9, 1943, now Patent 2,418,831, April 15, 1947. This housing consists of a mounting block 1 and two similar cover blocks 2 and 3, the three blocks being held together by screws 6, 7, 8. Screws 6 and 7 fit into threaded inserts or nuts 16, 17 (Fig. 3) molded into block 1 with their ends protruding into a recess 26 having an upper straight portion 21 and having a rounded bottom portion, as shown in Fig. 5. Holes 11, 12, 13 may be provided in blocks 1, 2, 3 for the purpose of suitably fastening the switch to a support. Ventilating slots 18, 19 may be provided as indicated in Fig. 3.

Two heat-responsive actuator strips 22, 23, for example of bimetallic construction, have on one side widened ends with holes 25 (Figs. 4 and 5) which are slipped over the protruding ends of inserts 16, 17, as shown in Fig. 3, recesses 28 preventing strips 22, 23 from rotating on the nuts. The strips are held in place by bosses 26, 27 of cover block 2, 3 (Fig. 3) which fit into recesses 28 of block 1.

The actuator strips may be provided with coils 32, 33 constituting heating resistances, preferably wound on insulating sleeves 34 of the type shown in Fig. 9. The ends of the heater wire or wires may be connected to terminal bars 36, 37, 38, 39 which have V-shaped deformations 41 and fit into corresponding recesses 42 of block 1 wherein they are positively confined by the cover blocks 2 or 3 when the blocks are screwed together. If one or both actuators are not to be artificially heated, some or all of these bars may be omitted, as for example indicated in Fig. 7 where actuator 123 is bare. In that case, mounting block 1 does not have recesses 42.

Molded into mounting block 1 are further two pivot bars 51, 52 whose protruding ends are provided with pivot notches 53, 54 (Figs. 1, 2).

A connecting means such as bar or rod 55 joins the free ends of actuators 22 and 23, the ends of bar 55 being secured within holes 24, for example by means of peripheral recesses 57 which arrangement provides pivots permitting free movement of the actuators while strictly maintaining their distance.

A switch spring 60 (Fig. 10) has two compression members or branches 61, 62 and therebetween a tension branch 63. The common portion 64 carries a contact point 65. The end of the tension branch 63 is shaped to engage an intermediate point, preferably a groove 69, of connecting bar 55, for example by means of a perforation 68 or a hook 68 (Fig. 10). The ends 73, 74 of the compression branches 61, 62 rest in the pivot notches 53, 54 of supports 51, 52. Tension branch 63 is shorter than compression branches 61, 62, so that the latter will buckle slightly when opening 66 engages connector 55 and the compression branches rest in notches 53, 54, provided of course that, as shown in the present instance, the notches are arranged approximately at the height of the connector.

In the figures, the contact 65 is shown in central position between faces 82 and 83; it will be understood that this position has been selected for the sake of convenient representation only

and that the movable contact will always rest on one or the other of these faces.

The contact point 65 cooperates with contact faces 82, 83 which are part of contact bars 84, 85 molded into cover blocks 2 and 3 which have recesses 86, 87 forming together a chamber confining the contact point 65. The contact bars 84, 85 are preferably L-shaped and bent outwardly, and protrude from blocks 2 and 3 with terminal ends 88 and 89 which, in order to provide proper spacing, may thus be staggered as indicated in Fig. 1. The terminal for the double throw switch spring 60, making contact either at 82 or 83, may be at 90, the circuit leading from contact point 65 through branch 63, bar 55, actuator 22 or 23, nut 16 or 17 to screws 6 or 7, either of which may be used as a terminal. If it is desired to use only a single stationary contact, as for example in the circuit of Fig. 12, one of the contact bars 88, 89 may be omitted, as shown in Figs. 6 and 7.

The above-described embodiment is especially well adapted for differential actuation when both actuators are provided with heaters as shown in Figs. 1 to 5, or for use with only one heater on a controlling actuator while the other actuator compensates for ambient temperature within the switch.

If it is desired to apply to one actuator the temperature of the general environment rather than that of the switch structure, an embodiment may be preferable which is similar to that shown in Figs. 6 and 7 which will now be described.

In the embodiment according to Figs. 6 and 7, a mounting block 101 carries threaded inserts or nuts 116, 117 holding actuators 122, 123 and connecting to terminal 190 in a manner similar to that described with reference to Figs. 1 to 5. The single heater coil 132 is connected to a pair of heater terminals 136, 137. The mounting block 101 is extended upwardly beyond spring 160 and forms one half 187 of the chamber which encloses contact point 165 and provides an insulated stop for this movable contact.

The contact face 182 of an L-shaped bar 184 is moulded into a cover block 102 which is fastened to block 101 by means of screws 106 and 108. Pivot supports 151, 152 with notches 153, 154 are again moulded into block 101, and the arrangement of actuators 122, 123, screws 106, 107, connecting bar 155, and switch spring 160 with branches 161, 162, 163 is similar to that described with reference to Figs. 1 to 5.

The connector 155 reaches actuator 123 through an opening 120 which, if desirable, may be lined with heat-insulating material. It will be understood that opening 120 can be made sufficiently wide to insure equal ambient temperature for both actuators; such a construction may for example be used in the circuit to be described with reference to Fig. 12.

The bare actuator 123 may be protected by a slotted cover plate 104 having a boss 121 fitting into the corresponding recess 142 of block 101 and holding actuator 123 by means of screw 107; a top flange 110 fits a corresponding groove of block 101. Holes 111, 112 may be provided for fastening the switch to a support.

If it is desired to apply the temperatures prevailing at two separate points by means of two bare actuator strips and to render the operation of the switch dependent upon the relation of these temperatures, an arrangement according to Fig. 8 may be used to advantage. In this figure, the mounting block 201 is provided with a flange 205 by means of which it can be fastened to

a wall 200 separating the spaces at different temperatures.

The block 201, similar to block 1 shown in Figs. 1 to 5, has moulded-in nuts 216 and 217 holding the actuator strips 222 and 223 and the notched pivot bars of which only bar 251 is shown. Connecting bar 255, together with the pivot bars, holds the switch spring 286 in the above-described manner. Nut 217 may be contained in a boss 218 of block 201 which protrudes through an opening in wall 200 and carries, fastened thereto by screw 201, a slotted cover plate 203. A second slotted cover plate 202, fastened to block 201 by screws 206 and 208, carries contact bar 288 moulded thereinto, opposite a contact bar 289 similarly fastened to block 201. The contact point 265 is arranged between contact faces 282 and 283 of bars 288 and 289, as above described. In order better to separate the medium surrounding actuator 223 from that surrounding actuator 222, a heat insulating bushing 250 may be provided for leading bar 255 through wall 200.

It will be understood that the current-carrying connection to the movable contact 65 must not necessarily lead through one of the actuator strips, but that it may be preferable to connect this contact directly with a conveniently placed terminal, for example through a flexible cord.

It will further be understood that the tension branch 63 of the switch spring must not necessarily be attached to the connector between the actuators 22 and 23, but that it may be arranged on the outside, as shown in Fig. 11. In this figure, 355 is the connector which correlates actuators 322 and 323 with switch spring 360. 332, 333 are the heater coils, 357 a notch of connector 355 for pivoting actuator 323, and 369 is a similar notch for the tension spring. Contact point 365 moves rapidly between fixed points 382, 383 when connector bar 355 is slightly moved in one or the other direction, by the combined effect of the actuators. It will be evident that, by appropriate choice of the lever arms, the tension forces and stresses involved can be selected at will, to suit any particular purpose. Similarly, the connector 55 may be of any convenient construction sufficiently strong to support the loads applied thereto.

The above-described devices operate as follows.

The pivot points 54, 57, 69 (Fig. 4) of the actuator and switch spring system are so adjusted that contact point 65 assumes under normal conditions the desired position either on contact face 82 or on face 83 (Fig. 3).

The actuators are so dimensioned and mounted that they provide the switching function desired for the purpose at hand. Referring for example to Figs. 1 to 5, if the actuators are mounted to deflect inwardly with rising temperature, if their rate of deflection is the same and their heater elements similar, the switch will remain in normal position so long as the currents in the respective coils are the same, in which case the equal tendencies to deflect in opposite directions cancel each other. If, however, one heating effect and hence the corresponding deflection outweighs the other, the switch will be operated. Assuming for example that point 65 rests normally on contact face 82 and that the actuators deflect inwardly with rising temperature, the contact point 65 will rapidly move from face 82 to face 83 when heater 32 becomes so much warmer than heater 33 that the deflection of

actuator 23 towards the left of Fig. 3 outweighs that of actuator 22 towards the right. Bar 55 will then move towards the left, thereby causing the lines of stress of the switch spring branches to pass each other and point 65 to move rapidly towards the right, connecting terminal 90 with terminal 88 instead of 86. At the same time, any ambient temperature effect is inherently excluded so long as the actuators are not deliberately kept separated as for example in the embodiment according to Fig. 8. It will be evident that, in arrangements similar to that of Figs. 1 to 5, any change in ambient temperature will affect both actuators equally but in opposite direction, the two virtual deflections cancelling each other. Upon reversal of the temperature relation of the two actuators, the switch will move back into initial position. It will be understood that the actuators must not necessarily deflect in opposite directions, although this is necessary for ambient temperature correction. Generally speaking, the switching operation will depend on a differential, additive or subtractive, effect of ambient and controllably impressed temperatures.

If only one heater element is used, as in the embodiment according to Figs. 6 and 7, the second actuator merely provides compensation for ambient temperature changes, rendering the effect of the actuating heater 132 independent of the ambient temperature so that it can be safely relied upon to operate the switch when its heating current attains a definitely determinable value.

In embodiments where the two actuators are not affected by the same ambient temperature conditions, as for example in that shown in Fig. 8, switches according to the invention can be operated responsive to an absolute difference of two temperature conditions. These temperatures may be either ambient ones or, if one or both actuators are provided with heating coils, a combination of ambient and superimposed control temperatures will be effective in operating the switch, as distinguished from the operation of switches according to Figs. 1 to 5, where a combination of two controllably impressed temperatures is effective, and of switches according to Figs. 6 and 7 where the absolute value of a controllably impressed temperature is effective.

Switches of the above-described type can be used in any circuit permitting the inclusion of heating elements and not requiring absolutely instantaneous operation, or where instantaneous operation is even undesirable but where two temperature conditions, one of which may be an ambient temperature, have to be exactly and positively correlated.

By way of example, a circuit will now be described whose accurate operation is made possible through temperature correlation according to the present invention, and in which the time lag inherent in this compensation is a beneficial factor.

Referring to Fig. 12, A and B are the terminals of an alternating current supply source, to which are connected a potential apportioning network N with impedances R1 and R2, and an electronic discharge device, for example a gas-filled cold cathode tube T with anode a, cathode k and control electrode c. Impedance R1 may be bridged by a variable-impedance detecting device, for example two electrodes or probes p1, p2 associated with a tank t for a liquid l. The control electrode c is connected to a point between impedances R1 and R2.

The heater coil 32 of bimetal strip 22 of a switch

S according to the present invention is connected in the anode circuit of tube T. The switch may be mounted in a housing according to Figs. 1 to 5; a single throw switch being used in this embodiment. An insulating stop as shown for example in Fig. 7 is indicated at 101. The contact indicated at 82 may be connected to terminal A through a signaling device D, and the terminal 88 of the switch spring 88 may be connected to terminal B. The potential apportioning network 10 may be so arranged that, when the probes p1, p2 are above the liquid level and constitute a high impedance, the potential of c is such that tube T is nonconductive. The switch S may be so arranged that, with the tube nonconductive, bar 15 88 is in a position retaining contacts 88, 82 open with blade 88 resting against stop 101.

In an arrangement of this type reliable compensation for ambient temperature is an important factor since, because of the comparatively low current and the correspondingly slight temperature changes available in the load circuit of such a device, variations in ambient temperature might be sufficient to cause false operation of an uncompensated switch.

In the circuit shown, control electrode c will normally have a potential effectively blocking current flow through the tube. Heater 32 then does not carry appreciable current and contact 88 rests against the insulating stop 101. If the water l in tank t rises until probes p1, p2 are conductively connected, the potential drop across impedance R1 will be decreased, the potential of c will rise and the tube become conductive. The output current flowing through coil 32 heats actuator 22 which moves bar 88 towards the right and causes point 88 to snap into contact with stationary contact 82, energizing signaling device D. Since both actuators tend to deflect towards the middle, and both are exposed to the same ambient temperature, no net motion results from variations in ambient temperature and the switch responds solely to changes of the tube output current.

The slight time lag between the firing of the tube and the closing of the switch upon coil 32 reaching the required temperature, which time lag can be easily adjusted to any suitable value, eliminates false operation in response to momentary effects, such as splashing of water over the probes. Another beneficial operating feature inherent in a circuit of this type is due to the purely ohmic character of the load resistance in the output circuit of the discharge tube. A load of this type utilizes all available energy, even of alternating current components of irregular wave shape. The current passing through a vacuum or gas tube to which an alternating voltage is applied, has the configuration of a rectified wave. The heating of the tube is proportionate to the effective or R. M. S. value of the current wave, but the useful power available to a conventional magnetic relay in the plate circuit of the tube is proportionate to the average current which is less than the R. M. S. value. If the unused alternating current component is by-passed around the relay by a condenser, this component contributes to the heating of the tube increasing the detrimental peak tube current, while it does not contribute in any way to the useful power of the relay.

If, according to the invention, a thermal relay is used, the power available therein is proportionate to the effective or R. M. S. value of the tube current which is greater than the average current; elimination of the alternating current bypass or smoothing condenser reduces the peak tube current. The conventional connection of a

condenser in parallel with a magnet coil in the output circuit of a tube, passes high surge currents, which are detrimental to the life of the tube. These surge currents can be limited by series resistances but only at some sacrifice in efficiency. If a pure resistance, as represented by the heater coil of the present relay, is used in the anode circuit, the peak current is limited to a value much lower than that obtainable in any circuit containing a capacitance.

From the foregoing description it will be apparent that the present invention is not dependent upon any particular construction of the snap switch proper but that the interconnected thermally controlled actuators may affect the operation initiating element of any switch that is at all suitable for this purpose. If the invention is applied to switches of the type herein described, it is not necessarily limited to constructions where connector 55 is attached to the tension member of the switch spring but, obviously, this connector can be fastened to the compression springs, so long as movement of the connector provides for relative movement of the spring branches causing passing of their lines of stress.

It should be understood that the present disclosure is for the purpose of illustration only and that this invention includes all modifications and equivalents which fall within the scope of the appended claims'

I claim:

1. A thermally controlled snap switch comprising: a support; a first thermal actuator, mounted on said support, having a free portion which moves in response to a temperature change; a second thermal actuator adapted to prevent motion of said free portion in response to an ambient temperature change equally effective on both actuators; two spring members joined together at one end, one spring member being so mounted on said support, and the other so secured to said free portion as to be subjected to opposite conditions of stress, and thereby arranged to cause abrupt movement of said joined ends when said free portion passes through a predetermined position relative to said support; an electrical contact arranged to be operated by said abrupt movement; and heating means arranged to cause differential heating of said actuators, and thus give rise to said abrupt movement.

2. A switch according to claim 1 in which said actuators comprise two bimetal strips, each strip having an end fixed to said support and a free end, and said free ends being connected by a rigid member.

3. A thermally controlled snap switch comprising: an actuating unit including two cooperating thermal actuators of such characteristics as to bend equally in response to a given temperature change, each actuator member having a mounting portion and a movable actuating portion; means for rigidly connecting said actuating portions; means for supporting said mounting portions so that the bending tendencies of said actuators oppose each other thereby preventing motion of said connecting means in response to a temperature change equally effective on both actuators; two spring members joined together at one end, one spring member being mounted on said supporting means, and the other so secured to said connecting means as to be subjected to opposite conditions of stress and thereby arranged to cause abrupt movement of said joined ends when said connecting means passes through a predetermined position relative to said

supporting means; an electrical contact arranged to be operated by said movement; and heating means associated in heat transfer relationship with one of said actuators.

4. A switch according to claim 3 wherein said connecting means comprises a rod, and the spring member secured thereto is pivoted with respect to the rod.

5. A switch according to claim 3 having two independent heating means, one associated in heat transfer relationship with each of said actuators, the position of said connecting means being determined by the differential in heating effect of said independent heating means.

6. A thermally controlled snap switch comprising: an actuating unit including two cooperating thermal actuators of such characteristics as to bend equally in response to a given temperature change, each actuator member having a mounting portion and a movable actuating portion; means for rigidly connecting said actuating portions; means for supporting said mounting portions so that the bending tendencies of said actuators oppose each other, thereby preventing motion of said connecting means in response to a temperature change equally effective on both actuators; a snap switch unit including a tension member, a compression member adjacent thereto and attached at one end to an end of said tension member, means for pivoting the unattached end of said tension member on said connecting means, and means for pivoting the unattached end of said compression member on said supporting means, said pivoting means being arranged to put said members under compression and tension, respectively, and thus cause rapid motion of said attached ends upon passing of the lines of stress of said members when said respective pivoting means are moved relative to each other; an electrical contact arranged to be operated by said rapid motion; heating means associated in heat transfer relationship with one of said actuators; and stops mounted on either side of said attached ends in fixed relation to said supporting means.

7. A thermally controlled snap switch comprising: a support; two bimetal strips having such heat-responsive characteristics, and each having an end so fixed on said support, as to bend equally in opposite directions in response to a change in ambient temperature; a rod rigidly connecting the free ends of said strips so as to combine their bending tendencies, thereby pre-

venting motion of said free ends in response to a temperature change equally effective on both strips; a snap switch unit including a tension member, a compression member adjacent thereto and attached at one end to an end of said tension member, means for pivoting the unattached end of said tension member on said rod, and means for pivoting the unattached end of said compression member on said supporting means, said pivoting means being arranged to put said members under compression and tension, respectively, and thus cause rapid motion of said attached ends upon passing of the lines of stress of said members when said respective pivoting means are moved relative to each other; an electrical contact arranged to be operated by said rapid motion; heating means associated in heat transfer relationship with one of said actuators; and stops mounted on either side of said attached ends in fixed relation to said supporting means, and a heating coil wound around one of said strips.

8. A switch according to claim 7 having a second heating coil wound around the other of said strips, the relative position of said pivoting means being determined by the differential in heating effect of said coils.
